CLAIM

The ornamental design for a stool, as shown and described.

DESCRIPTION

FIG. 1 is a perspective view of a stool in accordance with the present invention;

FIG. 2 is a top view of the stool shown in FIG. 1;

FIG. 3 is a bottom view of the stool shown in FIG. 1;

FIG. 4 is a left-side elevation view of the stool shown in FIG. 1; and,

FIG. 5 is a right-side elevation view of the stool shown in FIG. 1.

(Continued)

The broken lines in the drawings depict an environment of the stool and form no part of the claimed design.
